UNITED STATES PATENT OFFICE

LOUIS HERMAN ALFRED DUNKER, OF BIRMINGHAM, ENGLAND

CONSTRUCTION OF ROADS AND THE LIKE

Application filed May 27, 1926, Serial No. 112,123, and in Great Britain July 1, 1925.

The present invention has relation to a process of or means for manufacturing a road, more particularly to the surface covering or "carpeting" of concrete and like foundations, the invention having for its object to provide a surface covering or "carpeting" having a maximum resistance against wear and which is homogeneous and will avoid creeping and reduce local defects to a minimum. The present means also have the characteristic that when wear takes place, as it must inevitably after constant use, cavities, grooves, or the like of small diameter or transverse measurement are constituted and adapted to assist in preventing skidding of the wheels of vehicles.

According to the present invention I provide a reinforcing mesh comprised of a plurality of interengaged or interconnected flat section metal strips disposed with their major dimension vertically and adapted to be filled with asphalt, cement, concrete or the like to form a surface covering or "carpet" of a thickness equal or substantially equal to the aforesaid major dimension of the strip.

Such a surface covering or "carpet" is laid on top of a concrete asphalt or other foundation which may be reinforced or otherwise and from which it must be differentiated.

Seeing that the metal strips of the present surface covering or "carpeting" have their upper edges flush or substantially flush with the actual wearing surface of the road, such surface is rendered inevitably tough. As the section of road thus treated is covered with one continuous interwoven mat of steel it cannot creep or give.

The strip metal may have a major dimension of say $1\frac{1}{4}$ " and is formed to a zigzag or undulating formation, the respective apices or undulations being united or coupled by rods or like devices passing through perforations therein. Such rods or like devices not only connect the various metal strips, but ensure that the asphalt or other filling will not leave the cavities constituted by the mesh. Certain of these cavities may have a white filling to constitute the well-known "white line" for traffic guiding purposes.

The reinforcement mesh may be laid completely across the road on the foundation and the filling afterwards added; or, alternatively, the covering or "carpeting" may be formed as a plurality of relatively small "mats", each complete in its formation, and adapted to be applied to the road foundation and afterwards consolidated thereon to form the complete "carpet" or covering.

In order that this invention may be clearly understood and readily carried into practice, reference may be had to the appended explanatory sheet of drawings, upon which:

Figure 1 is a plan view of a reinforcement mesh constructed according to one form of the present invention.

Fig. 1^a is a fragmentary similar view as Fig. 1 showing a modification.

Figure 2 is a sectional elevation illustrating a road foundation upon which a surface covering or "carpeting" according to this invention has been applied.

Figure 3 illustrates in plan view a modified mesh.

In a convenient embodiment of the present invention I employ lengths of strip metal *a* of flat section steel (see particularly Figure 2) as for instance $1\frac{1}{4}$ " by $\frac{1}{16}$ " section and bend these strips to a zigzag formation (as illustrated particularly in Figure 1). The lengths of zigzag strip are aggregated together in the manner shown with the apices in engagement, and are held in such position by rods *b* which pass through perforations in the respective apices. These rods *b* may be arranged variously (as shown in the Figure 1) but it is desirable to ensure that some part of a rod spans or projects into each cavity constituted by the mesh.

The reinforcing mesh is laid flatwise upon the concrete or other road foundation *c* with its major dimension disposed vertically (shown particularly in Figure 2) and is filled with asphalt, concrete, cement or other desirable filling flush with the top edge of the mesh. Conveniently a thin layer of asphalt or grouting of cement may be initially placed upon the foundation, the mesh embedded upon such thin layer, and afterwards filled.

By arranging the rods *b* to span or project into each and every cavity there is no possibility of the asphalt or other filling leaving any particular cavity, seeing that it becomes well consolidated with a part of a rod. Certain of the cavities may have a white filling to constitute a "white line" for traffic guiding purposes, signs, etc.

In lieu of placing the reinforcing mesh upon the road foundation and afterwards filling it, the mesh may be filled to form a plurality of readily transportable "mats" which may be placed upon the road foundation and afterwards suitably consolidated by filling the joints with or without connecting the steel mesh in the different mats.

In lieu of uniting the metal strips by rods *b*, dumb-bell shaped devices of flat section, such as illustrated at *d*, in Fig. 1^a, may be employed, or rivets, bolts, pins, etc. of any suitable shape. These devices are passed through vertical slots in the strips and afterwards rotated through 90 degrees. In the modification shown in Figure 3 the strip metal *a* is bent to form a series of channels which are united by corner rods *b*, whilst in a still further modification (not illustrated), the strip metal may be bent to an undulating or wavy configuration for the purpose of this invention.

The present invention therefore consists in a covering or "carpeting" for a road foundation as differentiated from the foundation itself, which covering or "carpeting" has a metallic reinforcement extending completely through its thickness in the nature of strip metal or flat section bars, such a surface or covering having considerable wear-resisting characteristics, avoiding all creeping and local defects.

What I claim as my invention and desire to secure by Letters Patent is:—

1. A floor or pavement armoring comprising separate metal strips bent to zig-zag form, the strips having holes at the corners thus formed, and being assembled on edge with holes of adjacent strips in register and with the top edges substantially flush, whereby said top edges present a surface adapted, when the assembled armoring is incorporated in a floor or pavement structure, to lie flush with and armor the surface thereof, and rods extending through the openings and holding the strips in assembled position, the rods being of less length than the assemblage, whereby the assembled structure is flexible and adapts itself to the contour of the surface on which it lies.

2. A floor or pavement armoring comprising separate metal strips bent to zig-zag form, the strips having holes at the corners thus formed, and being assembled on edge with holes of adjacent strips in register and with the top edges substantially flush, whereby said top edges present a surface adapted,

when the assembled armoring is incorporated in a floor or pavement structure, to lie flush with and armor the surface thereof, and rods extending through the openings and holding the strips in assembled position, the rods being of less length than the assemblage and the metal strips being of less length than the width of such assemblage, whereby the assembled structure is flexible and adapts itself to the contour of the surface on which it lies.

3. A floor or pavement armoring comprising separate metal strips bent to zig-zag form, the strips having holes at the corners thus formed, and being assembled on edge with holes of adjacent strips in register and with the top edges substantially flush, whereby said top edges present a surface adapted, when the assembled armoring is incorporated in a floor or pavement structure, to lie flush with and armor the surface thereof, and rods of circular cross section extending through the openings and holding the strips in assembled position, the rods being of less length than the assemblage, whereby it is flexible longitudinally, and the metal strips being of less length than the width of the assemblage, whereby they may rock or turn around the circular rods, rendering structure flexible transversely.

4. A floor or pavement armoring comprising separate metal strips bent to zig-zag form, the strips having holes at the corners thus formed, and being assembled on edge with holes of adjacent strips in register and with the top edges substantially flush, whereby said top edges present a surface adapted, when the assembled armoring is incorporated in a floor or pavement structure, to lie flush with and armor the surface thereof, and rods of circular cross section extending through the openings and holding the strips in assembled position, the rods being of less length than the assemblage, whereby it is flexible longitudinally, and the metal strips being of less length than the width of the assemblage, whereby they may rock or turn around the circular rods, rendering the structure flexible transversely, the zig-zag strips being arranged in rows, the point of juncture of strips in one row being offset laterally of the assemblage relative to the point of juncture of strips in an adjacent row.

In witness whereof I have hereunto set my hand.

LOUIS HERMAN ALFRED DUNKER.
